CLAIM

I claim the ornamental design for a smart USB wall outlet, as shown and described.

DESCRIPTION

FIG. 1 is a perspective view of a smart USB wall outlet showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 rear, left and bottom side perspective view thereof. The broken lines shown in the drawings are for purpose of illustrating portions of the smart USB wall outlet that form no part of the claimed design.
